CLAIM

The ornamental design for a door unit for utility vehicle, as shown and described.

DESCRIPTION

FIG. 1 is a front view of a door of the door assembly of the present invention;
FIG. 2 is a rear view of a door of the door assembly of the present invention;
FIG. 3 is a side view of a door of the door assembly of the present invention;
FIG. 4 is an opposite side view of a door of the door assembly of the present invention;
FIG. 5 is a top view of a door of the door assembly of the present invention;
FIG. 6 is a bottom view of a door of the door assembly of the present invention;
FIG. 7 is a front perspective view of the rear panel of the door assembly of the present invention;
FIG. 8 is a front view of the rear panel of the door assembly of the present invention;
FIG. 9 is a perspective view of the rear panel of the door assembly of the present invention;
FIG. 10 is a top view of the rear panel of the door assembly of the present invention;
FIG. 11 is a bottom view of the rear panel of the door assembly of the present invention;
FIG. 12 is a front view of the front panel of the door assembly of the present invention;
FIG. 13 is a rear view of the front panel of the door assembly of the present invention;

FIG. 14 is a side view of the front panel of the door assembly of the present invention;

FIG. 15 is an opposite side view of the front panel of the door assembly of the present invention;

FIG. 16 is a top view of the front panel of the door assembly of the present invention;

FIG. 17 is a bottom view of the front panel of the door assembly of the present invention;

FIG. 18 is a front view of a flap of the door assembly of the present invention;

FIG. 19 is a rear view of a flap of the door assembly of the present invention;

FIG. 20 is a side view of a flap of the door assembly of the present invention;

FIG. 21 is an opposite side view of a flap of the door assembly of the present invention;

FIG. 22 is a top view of a flap of the door assembly of the present invention;

FIG. 23 is a bottom view of a flap of the door assembly of the present invention;

FIG. 24 is a front view of a header of the door assembly of the present invention;

FIG. 25 is a side view of a header of the door assembly of the present invention;

FIG. 26 is an opposite side view of a header of the door assembly of the present invention;

FIG. 27 is a top view of a header of the door assembly of the present invention;

FIG. 28 is a bottom view of a header of the door assembly of the present invention; and,

FIG. 29 is a front view of the door assembly of the present invention shown installed on a golf cart.

The broken lines shown in the FIG. 29 drawings view are for illustrative purposes only and form no part of the claimed design.
